UNITED STATES PATENT OFFICE.

CARL C. GERLACH, OF CLEVELAND, OHIO.

COMPRESSION REFRIGERATING-MACHINE.

1,207,893.

Specification of Letters Patent. Patented Dec. 12, 1916.

Application filed October 28, 1915. Serial No. 58,471.

To all whom it may concern:

Be it known that I, CARL C. GERLACH, a citizen of the United States, residing at Cleveland, in the county of Cuyahoga and State of Ohio, have invented certain new and useful Improvements in Compression Refrigerating-Machines; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in compression refrigerating machines and consists of a simple and efficient apparatus of this nature having various details of construction, combinations and arrangements of parts which will be hereinafter fully described, shown in the accompanying drawings and then specifically defined in the appended claims.

The invention consists further in the provision of an oscillating compression refrigerating machine, operated without a cooling medium other than air, in which a rapid circulation of air is caused by the oscillating movement of coil, thereby carrying off the heat of compression rapidly.

My invention is illustrated in the accompanying drawings, in which:

Figure 1 is a side elevation of the oscillating compressor, and Fig. 2 is an end view, a part being broken away.

Reference now being had to the details of the drawings by letter, A designate two standards rising from the base B and which are apertured at their upper ends to receive the horizontally disposed oscillating shaft C which has a longitudinal duct D therein adapted to communicate with the expansion coil F which in turn communicates with the condenser coil E through the pipe E', having a suitable valve H therein. Said condensing coil communicates with branching pipes J which in turn communicate with the ends of the oscillating cylinder L. A weighted lever O is mounted upon a pivot N mounted in the casing and has slotted pivotal connections at O' with the piston stem R which has pistons S thereon movable within said cylinder. Said casing has

an apertured lug T connected therewith through which power may be applied for the purpose of oscillating the same.

The parts being assembled in the manner shown, the operation of my invention is as follows:—When the casing is oscillated, the lever will remain stationary and also the pistons, while the cylinder moves back and forth and creates a suction power similar to that which would be produced if the piston were moved and the gases to be compressed and expanded are drawn through the pipe and forced into the condensing coil and thence pass to the expansion coil, the return of the latter being through the pipe D, thus making a complete cycle.

By the provision of an apparatus embodying the features of my invention, it will be understood that the means for removing the heat from the apparatus is produced by the rapid circulation of air which is caused by the oscillating movement of the coil and which will tend to carry off the heat of compression.

It will be noted that, in the operation of the apparatus, both the expansion and condenser coils oscillate with the casing while the pistons remain stationary.

What I claim to be new is:—

1. A refrigerating machine comprising standards, a shaft mounted therein provided with a duct, a condenser and an expansion coil oscillating with said shaft, a valve-regulated pipe communicating between the condenser and expansion coil, an oscillating casing and cylinder fixed to said shaft and communicating with the condenser coil, pistons within said cylinder, and pipe connections between the latter and the expansion coil.

2. A refrigerating machine comprising standards, a shaft mounted therein provided with a duct, a condenser and an expansion coil oscillating with said shaft, a valve-regulated pipe communicating between the condenser and expansion coil, an oscillating casing and cylinder fixed to said shaft and communicating with the condenser coil, pistons and stems connected thereto, and a weighted lever fixed to said stems and holding the pistons stationary as the casing oscillates.

3. A refrigerating machine comprising standards, a shaft mounted therein provided

with a duct, a condenser and an expansion coil oscillating with said shaft, a valve-regulated pipe communicating between the condenser and expansion coil, an oscillating casing and cylinder fixed to said shaft and communicating with the condenser coil, pistons and stems connected thereto, a weighted lever pivoted within the casing and hav-

ing slotted pivotal connection with said stems.

In testimony whereof I hereunto affix my signature in presence of two witnesses.

CARL C. GERLACH.
